US0D1026856S

(12) **United States Design Patent** (10) **Patent No.:** **US D1,026,856 S**
(45) **Date of Patent:** **** May 14, 2024**

(54) **PAIR OF WIRELESS EARPHONES**

(71) Applicant: **SHENZHEN GRANDSUN ELECTRONIC CO., LTD.**,
Guangdong (CN)

(72) Inventors: **Jiugao Peng**, Guangdong (CN);
Haiquan Wu, Guangdong (CN); **Tao Han**, Guangdong (CN); **Ruiwen Shi**,
Guangdong (CN); **Zhijun Zhang**,
Guangdong (CN); **Chuanqi Zhang**,
Guangdong (CN)

(73) Assignee: **Shenzhen Grandsun Electronic Co., Inc.**,
Guangdong (CN)

(**) Term: **15 Years**

(21) Appl. No.: **29/867,594**

(22) Filed: **Oct. 31, 2022**

(30) **Foreign Application Priority Data**

(57) **CLAIM**

The ornamental design for a pair of wireless earphones, as shown and described.

DESCRIPTION

FIG. 1 is a front perspective view of a pair of wireless earphones showing our design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the figures depict portions of the pair of wireless earphones that form no part of the claimed design.
